UNITED STATES PATENT OFFICE

134,718

DESIGN FOR A BUS

Thurston Crawford, Columbus, Ga.

Application June 20, 1942, Serial No. 107,277

Term of patent 14 years

To all whom it may concern:

Be it known that I, Thurston Crawford, a citizen of the United States, residing at Columbus, in the county of Muscogee, and State of Georgia, have invented a new, original, and ornamental Design for a Bus, of which the following is a specification, reference being had to the accompanying drawings forming a part thereof.

In the drawings,

Fig. 1 is a side elevational view of a bus showing my new design;

Fig. 2 is a plan view; and
Fig. 3 is a perspective view looking toward the front.

The rear portion of the bus design is conventional.

I claim:

The ornamental design for a bus, substantially as shown and described.

THURSTON CRAWFORD.
